IRONING BOARD

Filed Oct. 17, 1931

FRED J. SELLENTIN
INVENTOR.

BY *John P. Chandler*
his ATTORNEY.

UNITED STATES PATENT OFFICE

FRED J. SELLENTIN, OF NEWARK, NEW JERSEY

IRONING BOARD

Application filed October 17, 1931. Serial No. 569,383.

This invention relates to ironing boards which are adapted to be supported on the edge of a table or other projection, and the present application constitutes an improvement 5 on and a continuation in part of my co-pending application for ironing boards, Serial No. 511,673, filed Jan. 28, 1931.

The principal object of the present invention is to provide an ironing board having a 10 supporting leg pivotally mounted at one end thereof, and which, when the upper end of the supporting leg and the adjacent end of the board are placed in interlocking engagement with the edge of a table, the board will 15 be rigidly held in place for ironing.

Another object of the present invention is to provide an ironing board of the kind above referred to wherein the article will be durable, exceedingly simple in construction and 20 inexpensive to manufacture.

Still another object of the invention is to provide a table-engaging ironing board wherein the supporting leg structure will have convenient extension means for adjustment for use in connection with tables or 25 other projections of varying heights.

Other objects and advantages of the invention will be hereinafter specifically pointed out, or will become apparent, as the specification proceeds.

With the above indicated objects in view, the invention resides in certain novel constructions and combinations and arrangements of parts, clearly described in the following specification and fully illustrated in the accompanying drawing, which latter shows embodiments of the invention as at present preferred.

In the drawing:

Fig. 1 is a perspective view of the embodiment rigidly secured to the edge of a table.

Fig. 2 is a side elevation of the embodiment showing the supporting leg in a folded position.

Fig. 3 is a section taken on line 3—3 of

Fig. 1 and showing the supporting leg partly broken away.

Fig. 4 is a perspective view of the leg-extension member.

Fig. 5 is a broken perspective view of the upper end of the supporting leg.

Referring now to said drawing by reference numerals the present embodiment includes a flat, rectangular ironing board 10 constructed of wood or other suitable material, said ironing board having, at one end thereof, a longitudinal, vertical slot 11. Near the inner end of said slot, on opposite sides thereof, are located vertical apertures 12 and 13, said apertures extending from the lower surface 55 of said board through substantially two-thirds of the thickness thereof.

A U-shaped pivot member 14 constructed of round metal and having slightly out-turned end portions 15, the outturned end portions 65 causing the pivot member to be more securely held in said apertures.

A supporting leg 16 is constructed preferably from square wood and is provided with a transverse, rounded slot 17 near its 70 upper end, said slot being enclosed by rectangular plate 18 secured to said leg by means of screws 19, said plate having upturned flange portions 20 on each side thereof in order that when the leg is in a folded position as shown in Fig. 2 the flange portion will engage the sides of the slot and prevent the leg from moving to one side and out of line of the slot.

The upper end of the supporting leg is 80 preferably bevelled at 21 and an angle bar 22, constructed of iron or other suitable metal, is secured to the inner side of said supporting leg, by means of screws 23, the upper, horizontal portion 24 of said angle bar being 85 flush with said bevelled portion 21 of the supporting leg.

In order to prevent injury to the upper side of the table 25, to which the board is secured, the upper, horizontal portion of the angle 90

bar is provided with a cap 26 constructed of rubber or other resilient material, said cap having an extension portion 27 on the lower side thereof to partially cover the lower portion of the angle bar.

5 A leg extension member 30 is preferably constructed from a strip of sheet metal bent to a U shape, the lower end thereof 31 being turned inwardly to form a base portion. A 10 bolt 32 having a wing nut 33 is secured to said leg extension member, said bolt passing through a longitudinal slot 34 in the lower end of the supporting leg 16, the side portions 30' of the extension member engaging 15 the sides of the supporting leg 16. When it is desired to vary the length of the supporting leg the wing nut is loosened and the leg extension is adjusted to the proper length and the wing nut tightened. It will, of course, be 20 understood that the leg extension member may be adjustably secured to the supporting leg in any other known manner such as by securing the bolt in the latter and providing a longitudinal slot in the former through 25 which the bolt passes.

The hereinbefore described construction admits of considerable modification without departing from the invention; therefore, it is the wish not to be limited to the precise 30 arrangements shown and described, which are as aforesaid, by way of illustration merely. In other words the scope of protection contemplated is to be taken solely from the appended claim, interpreted as broadly as 35 is consistent with the prior art.

What I claim is:

An ironing board adapted to be detachably secured to the edge of a table or other horizontal projection and comprising an 40 elongated board member having a narrow, longitudinal, vertical slot extending inwardly from one end thereof, and having vertical apertures near the inner end of said slot, on each side thereof, extending upwards from 45 the lower surface of the board partially through its thickness, a U-shaped member constructed from round metal being force-fitted into said apertures, the vertical portions of said U-shaped member being slightly outwardly bent in order to be locked within 50 said apertures, the horizontal portion of the U-shaped member engaging the lower surface of the board to form a pivot member extending transversely of the longitudinal slot, an elongated supporting leg having, near its upper terminus, a transverse, circular recess adapted to receive the horizontal 55 pivot member, a rectangular plate secured 60 to said supporting leg adjacent to said recess and enclosing same, outwardly extending flange portions integral with the rectangular plate, said flange portions being adapted to engage the sides of the slot in the board and 65 adapted to prevent sidewise movement of

the leg when the latter is in a folded position, an angle bar secured to the upper end of said supporting leg, the upper portion of said angle bar being adapted to engage the upper side of a table, a protecting cap engaging the 70 upper portion of said angle bar, a U-shaped leg extension member slidably carried at the lower end of the supporting leg and adapted to vary the effective length of said supporting leg.

Signed at New York city, in the county of New York and State of New York this 29th day of September, A. D. 1931.

FRED J. SELLENTIN.
